Primary Examiner — Derrick Holland*Assistant Examiner* — Jennifer O King(74) *Attorney, Agent, or Firm* — Avery N. Goldstein; Blue Filament Law(57) **CLAIM**

The ornamental design for a handbag, as shown and described.

DESCRIPTION

FIG. 1 is a front view of a handbag showing my new design; FIG. 2 is a back view thereof;

FIG. 3 is a left side view of view thereof, where the strap is not shown for visual clarity, and the right side view is a mirror image of this view;

FIG. 4 is a bottom view thereof, where the strap is not shown for visual clarity;

FIG. 5 is a top view thereof, where the strap is not shown for visual clarity; and,

FIG. 6 is a perspective view thereof, where the strap is not shown for visual clarity.

The broken lines shown represent stitching and form part of the claimed design.
